JOHN J. MOUAWAD, OF NEWARK, NEW JERSEY, ASSIGNOR OF ONE-HALF TO ADBO
NASSOUR, OF NEWARK, NEW JERSEY.

STRAW-DELIVERING MECHANISM.

1,396,720.

Specification of Letters Patent. Patented Nov. 8, 1921.

Application filed May 26, 1920, Serial No. 384,429. Renewed July 20, 1921. Serial No. 486,185.

To all whom it may concern:

Be it known that I, JOHN J. MOUAWAD, a citizen of the French Republic, and resident of Newark, in the county of Essex and 5 State of New Jersey, have invented certain new and useful Improvements in Straw-Delivering Mechanism, of which the following is a specification.

This invention relates to dispensing devices for use particularly in holding and delivering drinking straws, the said invention having for its object the provision of novel means for housing or holding a stock of drinking straws in a manner to protect 10 them from the access of dust or insects and in a sanitary manner, novel means being provided for discharging or delivering a straw at a time as the delivering apparatus or mechanism is actuated, the said device 15 being so arranged as to guard against the delivery of more than one straw at a time thus avoiding undue waste of materials.

A still further object of this invention is to produce a delivering mechanism associated with means for agitating the straws 20 in the holder or container to insure proper delivery of the straws to the discharge opening of the device.

A still further object of this invention is 25 to produce an actuating mechanism for effecting the delivery of the straws and in the provision of means for holding the delivering mechanism inactive to prevent tampering with the said mechanism as might be done by curious persons or children to the detriment of the user or proprietor of the device.

A still further object of this invention is 30 to produce a device of the character indicated which can be made comparatively inexpensive, while at the same time, it will possess strength and durability and prove efficient and satisfactory in use.

With the foregoing and other objects in 35 view, the invention consists in the details of construction, and in the arrangement and combination of parts to be hereinafter more fully set forth and claimed.

In describing the invention in detail, reference will be had to the accompanying 40 drawings forming part of this specification wherein like characters denote correspond-

ing parts in the several views, and in which—

Figure 1 illustrates a perspective view of 55 a holder and distributing device embodying the invention;

Fig. 2 illustrates a perspective view of 60 part of the agitating and delivering mechanism detached from the casing;

Fig. 3 illustrates a transverse sectional view of the said device in its normal condition;

Fig. 4 illustrates a transverse sectional view of the said device on a different line 65 from that of Fig. 3, showing the parts in position for delivering the straws;

Fig. 5 illustrates a sectional view on the line 5—5 of Fig. 3 with the rear wall of the 70 pedestal removed, and

Fig. 6 illustrates a perspective view of the exit door.

In these drawings 10 denotes a base, 11 a pedestal, 12 a hopper having a hinged cover 13 and a transparent front wall 14. The 75 foregoing parts are illustrated for the purpose of conveniently disclosing an embodiment of the invention, but it is to be understood that these parts may be modified or changed in proportions or configuration 80 without departing from the scope of the invention as set forth in the claims.

The hopper is preferably provided with a forwardly curved bottom and an apron or partition 15 spaced from and parallel 85 with a front wall 14, the width of the space being preferably slightly greater than the diameter of the straw so that the straws could drop into the space, one above the other and gravitate therein upon the removal of the undermost straw and the next succeeding straw would be situated in position for delivery upon the re-actuation of the delivering mechanism.

At the lower edge of the front wall 14 95 there is an exit opening 16 through which straws are delivered in a manner to be presently explained and the straws are prevented from escaping through this opening by a door 17 having pintles 18 on its ends 100 which are journaled in the end walls of the hopper, and the door is of such a nature as to close by gravity and its weight is sufficient to prevent the straws from forcing it open

except when the said straws are pushed by the actuating mechanism.

Brackets 19 project outwardly under the exit opening and they are curved as shown so that the straws will fall on the brackets from whence they can be removed by the prospective user.

The straw actuating or dislodging mechanism comprises a shaft 20 journaled in the base in any appropriate manner and having an arm 21 rigid therewith which arm projects through a slot or opening 22 in the base and is provided with a key 23 which can be pushed for oscillating the arm and partially rotating the shaft 20.

The shaft 20 is further supplied with up-standing arms 24-24. Each of said arms has a plunger 25 connected to it by a pivot 26, and each plunger projects through an opening 27 in the bottom of the hopper and is adapted to bear against the lowermost straw between the partition and the front wall of the hopper to force the said straw outwardly for the purpose of discharging it, it being shown in Fig. 4 that when this operation occurs, the door 17 is swung outwardly, it being understood that the said door returns to its normal position, shown in Fig. 3, by gravity. Each arm is further provided with a shank 28 having agitating fingers 29 each of which projects through a slot 30 in the bottom of the hopper into position to engage straws in the hopper for the purpose of agitating them and forcing them toward the discharge opening. The shaft 20 is further provided with a coil spring 31 having one end anchored to the said shaft, as at 32, the opposite end of said spring terminating in an extension 33 which bears against the under side of the base to maintain the tension of the spring which is operative to retract the plungers and restore the parts to normal position for a repetition of the operation just described. In order to prevent undue operation or manipulation of the straw delivering mechanism, a guard 34 is slidably mounted in the guide 35 which is secured to the inner surface of the base, and the guard has an extension 36 which may be forced under the arm 21 to prevent movement of the arm.

The guard has a notch 37 into which the end of a lever 38 projects, the said lever being mounted on a pivot 39 in the base, the said lever having a projection 40 at the rear which may be operated by someone from the rear who is desirous of preventing the operation of the straw delivering mechanism, and this would be of importance should children start to operate the delivery mechanism for amusement, as often occurs with new devices of this character, when an attendant of the store could operate the guard

to prevent the delivering mechanism being operated.

65

I claim:

1. In a straw delivering mechanism, a hopper having an inclined bottom and a depending partition at the front edge of the said bottom, the said hopper having a front wall, the lower part of which is parallel to and spaced from the partition to produce a clearance for the passage of straws, the said wall having a discharge opening at the lower edge thereof, a door pivotally mounted in position to guard the said opening, plungers mounted to operate in conjunction with the lowermost straw at the discharge opening, arms to which the plungers are pivotally connected, fingers carried by the said arms and projecting into the hopper for agitating the straws, and means for oscillating the arms.

2. In a straw delivering mechanism, a hopper having an inclined bottom and a depending partition at the front edge of the said bottom, the said hopper having a front wall, the lower part of which is parallel to and spaced from the partition to produce a clearance for the passage of straws, the said wall having a discharge opening at the lower edge thereof, a door pivotally mounted in position to guard the said opening, plungers mounted to operate in conjunction with the lowermost straw at the discharge opening, arms to which the plungers are pivotally connected, fingers carried by the said arms and projecting into the hopper for agitating the straws, a shaft on which the arms are carried, an operating arm for partially rotating the shaft and a spring for returning the parts to normal position.

3. In a straw delivering mechanism, a hopper having an inclined bottom and a depending partition at the front edge of the said bottom, the said hopper having a front wall, the lower part of which is parallel to and spaced from the partition to produce a clearance for the passage of straws, the said wall having a discharge opening at the lower edge thereof, a door pivotally mounted in position to guard said opening, plungers mounted to operate in conjunction with the lowermost straw at the discharge opening, arms to which the plungers are pivotally connected, fingers carried by the said arms and projecting into the hopper for agitating the straws, a shaft on which the arms are carried, an operating arm for partially rotating the shaft, a spring for returning the parts to normal position, means for oscillating the arms, and means for holding the oscillated means against movement.

JOHN J. MOUAWAD.

Witness:

DAVID J. FORMAN, J. P.
